UNITED STATES PATENT OFFICE.

HARRY SNYDER, OF OAKLAND, CALIFORNIA.

ADJUSTABLE HEEL REST.

Application filed October 5, 1921. Serial No. 505,474.

To all whom it may concern:

Be it known that I, HARRY SNYDER, a citizen of the United States, residing at Oakland, in the county of Alameda and State of California, have invented new and useful Improvements in Adjustable Heel Rests, of which the following is a specification.

This invention relates to a foot rest, and especially to such rests as are employed by 10 the drivers of motor vehicles and the like.

One of the objects of the present invention is to generally improve and simplify foot rests of the character described; to provide a foot rest which may be readily 15 applied to the foot board of any standard motor vehicle in use today; a foot rest which will serve as a protection for the foot board, and particularly the mat or covering usually employed, and above all a foot rest which is 20 universally and freely movable within limits to any position required when the foot throttle or the brake pedal is to be employed.

Further objects will hereinafter appear.

25 The invention consists of the parts and the construction, combination and arrangement of parts as hereinafter more fully described and claimed, having reference to the accompanying drawings, in which—

30 Fig. 1 is a side elevation of the foot rest showing its position on the foot board with relation to the throttle lever.

Fig. 2 is a central, vertical, longitudinal section of the foot rest or in other words the 35 heel support.

Fig. 3 is a plan view of the base portion.

Fig. 4 is a plan view of the heel rest and the base by which it is supported.

Referring to the drawings in detail, and 40 particularly to Fig. 1, A indicates in general the foot board of an automobile or like vehicle, 2 the throttle lever or accelerator, 3 the foot of the operator or driver, and 4 the rest by which the foot and particularly 45 the heel is supported when the car is being driven.

The foot rest more particularly described is in reality the heel cap so supported that 50 universal and free movement of the foot within limits to any position required will be permitted. This is accomplished in the following manner: 5 indicates a base plate constructed of fairly heavy sheet metal or like material. The plate is preferably 55 formed between a pair of dies and when so treated a spherical or socket portion 6

is formed centrally of the plate. Also formed in the plate is a semi-circular opening 7. This opening is formed adjacent the top of the sphere, one side presenting a straight line 8 and the other side a curve or semi-circle as at 9. Forming a cover and a closure for the top of the sphere, and particularly the opening 7, is a plate 10, and disposed on the inner side of the sphere is a similar plate 11. These plates are also preferably formed between the dies and are in reality nothing more or less than circular sections of a spherical surface; the radius being identical to that of the sphere 6, so that perfect engagement between the sphere 6 and the plates 10 and 11 is obtained. Securing the plates with relation to each other is a pin or rivet 12, and supported by the upper plate 10 is a heel cap or plate consisting of a base portion 13 and a semi-circular side flange 14. The pin or rivet indicated at 15 does not only extend through the plates 10 and 11, but also through the base 13 of the foot rest. The three members are thus secured as an integral unit and will move in unison whenever movement is imparted thereto. The pin 15 extends through the opening 7 and rearward movement of the heel rest is limited by the straight side 8. Rocking movement to either side is permitted and forward movement within the limits of the curved portion 9 is permitted in any direction. A universal mounting 90 and support is therefore provided which permits movement of the foot within limits to any position required when the foot throttle 2 or the brake pedal not here illustrated is to be employed. This is of considerable importance as it permits perfect freedom of action when control of the automobile is considered and relieves the driver from strained or cramped positions, incident to rigid foot rests and the like.

100 The foot rest further serves as a protection for the mat usually present in the driving compartment of the automobile, and for the foot board proper. It is so constructed that it may be readily adjusted with relation to any of the pedals desired, and as it is secured in position by means of nails or screws passed through the openings indicated at 16, it can be seen that it may be installed in any standard form of motor vehicle or car in use today.

110 The inner or upper surface of the base

portion 13 may be corrugated or covered with an anti-friction padding, if desired. The size of the foot rest may be increased or decreased to suit various conditions or 5 size of shoes, and the materials and finish of the several parts employed may be such as the experience and judgment of the manufacturer may dictate or varying uses may demand.

10 Having thus described my invention, what I claim and desire to secure by Letters Patent is—

1. A heel rest of the character described, comprising a spherical-shaped base portion, 15 a member attached to the base portion and universally movable with relation thereto, and a heel rest secured to said member.

2. A heel rest of the character described, comprising a base plate, a spherical shaped 20 support formed thereon, an opening formed

in the upper portion of said spherical support, a pair of spherical shaped plates, one disposed on each side of said opening and forming a closure therefor, a heel rest supported by the uppermost plate, and a pin 25 extending through the heel rest and both of the plates and securing the same as a unit.

3. A heel rest of the character described, comprising a spherical shaped support, a base plate formed in a part thereof, a semi-circular shaped opening formed by the apex of the sphere, a pair of cover plates carried by the sphere, one on the upper surface and one on the inner surface, a pin 30 extending through said plates and the semi-circular opening formed in the apex of the spherical shaped supporting member, and a heel rest carried by the uppermost plate and secured by said pin.

HARRY SNYDER.
